(57) **CLAIM**

The ornamental design for a foldable prone support, as shown and described.

DESCRIPTION

FIG. 1 is a left side perspective view of a foldable prone support in its open position showing my new design;

FIG. 2 is a front perspective view of a foldable prone support in its open position;

FIG. 3 is an alternate front perspective view of a foldable prone support in its open position;

FIG. 4 is a back perspective view of a foldable prone support in its open position;

FIG. 5 is a right perspective view of a foldable prone support in its open position;

FIG. 6 is a left perspective view of a foldable prone support in its open position;

FIG. 7 is a top perspective view of a foldable prone support in its open position;

FIG. 8 is a bottom perspective view of a foldable prone support in its open position;

FIG. 9 is a left side perspective view of a foldable prone support in its closed position;

FIG. 10 is a front view of a foldable prone support in its closed position;

FIG. 11 is a back perspective view of a foldable prone support in its closed position;

FIG. 12 is a right side view of a foldable prone support in its closed position;

FIG. 13 is a left side view of a foldable prone support in its closed position;

FIG. 14 is a top view of a foldable prone support in its closed position;

FIG. 15 is a bottom perspective view of a foldable prone support in its closed position; and,

FIG. 16 is a left side perspective view of a foldable prone support in its partially open position.

Right side perspective views not shown are mirror images of left side perspective views. Any broken line illustration of environmental structure in the drawings are not part of the design sought to be patented.
